UNITED STATES PATENT OFFICE.

HENRY W. O'DOWD, OF JERSEY CITY, NEW JERSEY, ASSIGNOR TO WILLIAM M. CRANE COMPANY, A CORPORATION OF NEW YORK.

SAD-IRON.

1,228,043.

Specification of Letters Patent. Patented May 29, 1917.

Application filed September 18, 1912. Serial No. 720,204.

To all whom it may concern:

Be it known that I, HENRY W. O'Dowd, a citizen of the United States, and a resident of Jersey City, Hudson county, State of New Jersey, have made certain new and useful Improvements in Sad-Irons, of which the following is a specification.

The invention relates to sad irons, and more particularly to that kind of sad iron which is heated by a gas burner contained in the iron.

Objects of the invention are to provide an improved device of the character referred to which, while simple and durable in construction, shall be highly efficient and economical and safe in operation; and which shall be particularly adapted for use with natural gas. These and other objects of the invention will in part be obvious and in part be more fully explained in the following description.

The invention consists in the novel parts, improvements, combinations, and features of construction herein shown and described.

In the accompanying drawings, which are referred to herein and form a part hereof, is illustrated an embodiment of the invention, the same serving in connection with the description herein to illustrate the principles of the invention.

Of the drawings:

Figure 1 is a vertical central section, taken on the line 1—1 of Fig. 3, of a sad iron constructed in accordance with the invention;

Fig. 2 is a cross-section, taken on the line 2—2 of Fig. 1, a part being shown in perspective;

Fig. 3 is a top view of the body of the iron with the top removed;

Fig. 4 is a perspective of a detail; and

Fig. 5 is a perspective of the rear wall of the iron showing a preferred form of burner used in the embodiment of the invention illustrated and passages for atmospheric air to support combustion.

A sad iron constructed in accordance with certain features of the invention includes a casing forming a chamber, a plurality of grooves in the bottom of said chamber, a burner arranged at the rear of said chamber and having inwardly directed perforations, a baffle arranged longitudinally in said chamber above said burner, and openings in the sides of said chamber for the admission of air to support combustion.

According to certain other features of the

invention, said burner comprises an oblong chamber extending transversely of the first mentioned chamber, has a gas inlet on its outer side and a multiplicity of inwardly directed perforations in its inner side; additional openings for the admission of air to support combustion are formed in the rear wall of said chamber in the iron above said burner; and said baffle has its rear portion extended upwardly toward and above said openings in the rear wall.

These and other features of the invention will be more fully explained in the following description.

Referring now in detail to the drawings, the embodiment of the invention illustrated comprises a casing 7 forming a chamber 8. In order that the heat may be quickly and advantageously distributed through the bottom of the iron or chamber in a manner that will be apparent, a plurality of longitudinally extending grooves 10 are formed in the bottom of said chamber 8.

Preferably and as shown, a burner 11 is arranged in the rear of the chamber 8 and is oblong in shape, its outer side being formed by the rear wall 12 of the casing and its other sides extending into the chamber 8. A threaded opening 13 is formed in said outer side in which is fitted the usual Bunsen tube, not shown. In the inner side of the burner are formed a multiplicity of inwardly directed small perforations 15. It will be noted that these numerous small perforations are particularly advantageous for the combustion of gas at high pressure, as natural gas, and that as the perforations are distributed throughout the entire length of the inner face of the burner, the flames will be distributed over the entire transverse extent of the bottom of the chamber.

In order to support combustion, openings 17 for the admission of atmospheric air are, in the embodiment illustrated, formed in the rear wall 12 of the chamber 8, preferably above said burner 11 and distributed from side to side of said wall 12. It is to be noted that the cold air entering through said openings will not only support combustion but by reason of its downward flow over the burner will give direction to the heated products of combustion, causing them to flow over the bottom of the iron. In its downward passage this atmospheric air, as shown, is also guided by the rear portion 19 of a baffle plate 20, said portion 19 extending from

side to side of the chamber 8 and preferably forming an arch extending toward and above the said openings 17, the advantage of this shape in guiding the atmospheric air 5 being apparent. Said baffle plate 20 is provided for the purpose of increasing the efficiency of the iron by forcing the heated products of combustion to pass through the chamber 8 close to the bottom thereof, and, 10 hence, as shown, it extends longitudinally between the planes of the openings 17 and the burner 11 throughout the major portion of the length of the chamber 8 and from side to side. As will be seen, an opening is provided at the forward end of the plate 15 through which the heated products of combustion pass on their journey to the atmosphere through, preferably, a vent at the top of the chamber formed by raising the edge 20 22 of the top, see Figs. 1 and 2, on the side away from the operator. In the embodiment shown it has been found advantageous to provide further openings 23 in the sides and forward end, respectively, of the baffle 25 to promote circulation. The baffle 20 rests on lugs 24 and is held in place by a depending lug 25 from the top of the casing bearing against a lug 26 upstanding from the baffle 20. To provide a further supply of atmospheric air to support combustion, openings 28 are formed in the opposite sides of the casing, preferably, below the level of the baffle 20 and at points suitably spaced apart. 30 To secure the operator against injury a second top 30 with handle 31 is provided, said top being spaced apart from the lower or main top of the casing by lugs 33 suitably disposed on the said lower top, both said tops being suitably secured to the casing 7, 35 as by screws 35 fitting in suitably threaded recesses in the casing.

It will be seen that a sad iron constructed as herein shown and described carries out the objects of the invention besides possessing 40 other advantages which will be apparent to those skilled in the art.

The invention in its broader aspect is not limited to the precise construction shown and described, as many changes may be made in 50 the details thereof within the scope of the claims without departing from the main principles of the invention or sacrificing its chief advantages.

I claim:

55 1. A sad iron including in combination, a casing forming a chamber, a burner in said casing, openings in the rear wall of said chamber above said burner, and a baffle arranged longitudinally in said chamber between said burner and said openings and having its rear portion extended upwardly toward and above said openings.

60 2. A sad iron including in combination, a casing forming a chamber, a burner arranged at the rear of said chamber and hav-

ing inwardly directed perforations, openings in the rear wall of said chamber above said burner, and a baffle arranged longitudinally in said chamber between said burner and said openings and having its rear portion 70 extended upwardly toward and above said openings.

3. A sad iron including in combination, a casing forming a chamber, a burner arranged at the rear of said chamber and having inwardly directed perforations, openings in the rear wall of said chamber above said burner, a baffle arranged longitudinally in said chamber between said burner and said openings and having its rear portion 75 extended upwardly toward and above said openings in the rear wall, and additional openings in the sides of said chamber below said baffle for the admission of air to support combustion, and a vent in the top of 80 said chamber.

4. A sad iron including in combination, a casing forming a chamber, a burner arranged at the rear of said chamber and having inwardly directed perforations, openings 90 in the rear wall of said chamber above said burner, a baffle arranged longitudinally in said chamber between said burner and said openings and having vents in its side and front for the passage of the heated products 95 of combustion and having its rear portion extended upwardly toward and above said openings in the rear wall, and additional openings in the sides of said chamber below said baffle for the admission of air to support combustion, and a vent in the top of 100 said chamber.

5. A sad iron including in combination, a casing forming a chamber, a burner arranged at the rear of said chamber and having inwardly directed perforations, a plurality of grooves in the bottom of said chamber, openings in the rear wall of said chamber above said burner, a baffle arranged longitudinally in said chamber between said 105 burner and said openings and having its rear portion extended upwardly toward and above said openings, additional openings in the sides of said chamber below said baffle for the admission of air to support combustion, and a vent in the upper portion of said chamber.

6. A sad iron including in combination, a casing forming a chamber, a burner arranged at the rear of said chamber and having inwardly directed perforations, a plurality of grooves in the bottom of said chamber, openings in the rear wall of said chamber above said burner, and a baffle arranged longitudinally in said chamber between said burner and said openings and having its rear portion extended upwardly 120 toward and above said openings.

7. A sad iron including in combination, a casing forming a chamber, and a burner ar- 130

- ranged at the rear of said chamber, said burner comprising a chamber extending transversely of the rear wall of said first mentioned chamber and having a gas inlet 5 in its outer side and in its inward side a multiplicity of inwardly directed perforations.
8. A sad iron including in combination, a casing forming a chamber, a burner located 10 at the rear of said chamber and having a multiplicity of inwardly directed perfora-

tions, the bottom of said casing being formed with a plurality of grooves therein, and a baffle arranged longitudinally in said chamber above the burner.

In testimony whereof, I have signed my name to this specification, in the presence of two subscribing witnesses.

HENRY W. O'DOWD.
